UNITED STATES PATENT OFFICE.

GEORGE FENWICK AND MARIE NEVA FENWICK, OF VENICE, CALIFORNIA.

DESIGN FOR AN AUTOMOBILE HEADLIGHT.

Application filed May 10, 1924. Serial No. 9,553. Term of patent 14 years.

To all whom it may concern:

Be it known that we, GEORGE FENWICK and MARIE NEVA FENWICK, citizens of the United States, residing at Venice, in the county of Los Angeles and State of California, have invented a new, original, and ornamental Design for Automobile Headlights, of which the following is a specification, reference being had to the accompanying drawing, forming part thereof.

Figures 1 and 2 of the drawing respectively are three quarter and front views of an automobile headlight showing our new design.

We claim:

The ornamental design for an automobile headlight, as shown.

GEORGE FENWICK.
MARIE NEVA FENWICK.
